Patented Dec. 26, 1961

192,001

BICYCLE CHAIN GUARD

Bertram Scheuer, Miami Beach, Fla., assignor to Bert Scheuer, Inc., New York, N.Y., a corporation of New York

Filed Mar. 30, 1960, Ser. No. 59,944

Term of patent 7 years

(Cl. D90—5)

Fig. 1.

Fig. 2.

Fig. 3.

Fig. 4.

Fig. 5.

FIGURE 1 is a top plan view of a bicycle chain guard embodying my new design;

FIGURE 2 is a front elevational view thereof;

FIGURE 3 is a bottom plan view thereof;

FIGURE 4 is a right end elevational view thereof; and

FIGURE 5 is a vertical, cross-sectional view thereof taken along the line 5—5 of FIG. 2.

The dominant features of my design reside in the full-line portions of the drawing.

I claim:

The ornamental design for a bicycle chain guard, as shown and described.
